UNITED STATES PATENT OFFICE.

JOHN T. ROWLEY, OF BEAVER FALLS, AND JOHN R. CAVANAGH, OF PITTSBURG, PENNSYLVANIA.

BURGLAR-ALARM.

SPECIFICATION forming part of Letters Patent No. 636,292, dated November 7, 1899.

Application filed May 21, 1898. Serial No. 681,357. (No model.)

To all whom it may concern:

Be it known that we, JOHN T. ROWLEY, residing at Beaver Falls, in the county of Beaver, and JOHN R. CAVANAGH, residing at 5 Pittsburgh, in the county of Allegheny, State of Pennsylvania, citizens of the United States, have invented certain new and useful Improvements in Burglar-Alarms; and we do hereby declare the following to be a full, clear, 10 and exact description thereof, reference being had to the accompanying drawings, which form a part of this specification, in which —

Figure 1 indicates a plan view of our improved burglar-alarm. Fig. 2 is a front elevation of the same. Fig. 3 is a side elevation of the same, dotted lines indicating finger in position at discharge of cartridge. Fig. 4 is a view of door-plate. Fig. 5 is a side elevation of alarm as attached to window-sash. Fig. 6 20 is a view of window-sash plate.

Our invention relates to devices adapted to be fastened and adjusted upon doors, windows, &c., for the purpose of giving an alarm when an attempt is made to open said door or window while the alarm is operatively affixed thereto; and to this purpose our invention consists of the novel construction and arrangement of parts hereinafter described, reference being had to the accompanying 25 drawings, which form a part of this specification, in which like reference characters indicate like parts wherever they occur.

Referring now to said drawings, 1 is a box or case adapted to be screwed or otherwise suitably secured to the side of a door, adjacent to the frame or jamb thereof or upon the window-sash. The said box is provided with a slot 2 intermediate its length, transversely the same, for the purpose hereinafter specified and with a slot 3 in the forward end thereof, longitudinally thereof, extending from the transverse slot to the upwardly-projecting abutment or part 4 at the extreme forward end of the case, said upwardly-projecting abutment being provided with an orifice 5 for the reception of a cartridge or cap 6. The said box or case is provided with openings 7 at either end thereof, in which the ends of the bolt 8 project, the said bolt being provided with an 30 outwardly-projecting finger 9, which is adapt-

ed to project in said slots 2 and 3. Said bolt is also provided on its lower side, directly opposite said finger, with a short projection or notch 10, between which and the rear end of the box is loosely mounted on said bolt a coil-spring 11. The forward end of said finger is provided with a projection or pin 12, adapted when said finger is forced forward by the retraction of said spring to explode the cartridge or cap secured in said opening. A 35 plate 13, secured to the jamb or frame of the window in any suitable manner, is adapted to maintain the spring compressed when the finger is adjusted in operative position and is provided with an opening 14, into which the 40 forward end of the bolt is adapted to pass when the door is forced open, thus permitting the bolt to travel a sufficient distance to bring the finger in contact with the cap or cartridge, exploding the same and at the same time 45 bolting the door.

When at any time it is desirable not to set the alarm, the bolt is drawn rearwardly sufficient to permit the finger to be thrown either upwardly or downwardly in the slot, where 50 the bolt is held out of contact with the plate on the door-frame and rearwardly of the edge of the door when the same is open, permitting the same to fully open and shut without interfering with the alarm. When the door 55 is closed at night, the finger is thrown into alignment with the slot and cartridge. An effort to open the door when the alarm is so adjusted will operate to discharge the cap or cartridge, as heretofore specified.

Having described our invention, what we claim, and desire to secure by Letters Patent, is —

In a burglar-alarm, a case having a vertical slot intermediate the same and a longitudinal slot extending from said vertical slot toward the front of the casing, an upwardly-projecting abutment having an orifice adapted to receive a cap or cartridge the said orifice being in alignment with said longitudinal slot, a bolt mounted in said case having a spring mounted thereon between a notch in the lower side thereof and the rear end of the case and having an outwardly-projecting finger integral therewith adapted to project in the slots 100

in said case and to engage in the vertical slot and when said spring is retracted to strike said cap or cartridge, in combination with a perforated plate adapted to be fixed to the 5 jamb of a door or a window-frame, substantially as set forth.

In testimony whereof we have hereunto af-

fixed our signatures in the presence of two subscribing witnesses.

JOHN T. ROWLEY.

JOHN R. CAVANAGH.
